UNITED STATES PATENT OFFICE.

JOSEPH C. CADY, OF NORTHFIELD, VERMONT.

COW-TAIL HOLDER.

SPECIFICATION forming part of Letters Patent No. 350,114, dated October 5, 1886.

Application filed July 19, 1886. Serial No. 208,477. (No model.)

To all whom it may concern:

Be it known that I, JOSEPH C. CADY, of Northfield, in the county of Washington and State of Vermont, have invented a new and 5 useful Cow-Tail Holder, of which the following is a specification.

The invention relates to that class of devices commonly known as "cow-tail holders," the object being to provide a simple and cheap 10 device adapted to clamp the hock and tail of the cow and prevent annoyance to the milker or injury to the cow.

To this end it consists in the construction hereinafter described, and pointed out in the 15 claim.

The accompanying drawing, forming part of this specification, is a plan view of my invention.

The device consists of a single piece of tempered wire coiled nearly midway of its length 20 to form the spring A, the ends forming the arms B B', which are, at a suitable distance, bent to pass or traverse each other, and are again bent to form the long and short curved 25 extensions B² B³, as illustrated in the drawing.

The operation of the device is very simple. The milker takes the holder in his or her hand, (preferably the left,) and securing the tail within the curved extension B³ the arms B B' are pressed together, separating the curved 30 extensions B² B³, which are passed about the leg of the cow just above the gambrel-joint, when the pressure is relaxed and the tail is held to the leg by the holder. To remove the device, it is only necessary to press the arms 35 B B' together, separating the curved extensions.

Having fully described my invention and its operation, what I claim, and desire to secure by Letters Patent, is—

A cow-tail holder consisting of a single piece 40 of tempered wire coiled to form the spring A and arms B B', which arms are bent to pass or traverse each other and again bent to form the curved extensions B² B³, substantially as described.

JOSEPH C. CADY.
